OWEN BROOKE EVANS, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

MANUFACTURE OF CARBURETED WATER-GAS.

1,125,676.

Specification of Letters Patent. Patented Jan. 19, 1915.

Application filed February 20, 1912. Serial No. 678,756.

To all whom it may concern:

Be it known that I, OWEN BROOKE EVANS, a citizen of the United States, and a resident of Philadelphia, in the county of Philadelphia and State of Pennsylvania, have invented certain new and useful Improvements in the Manufacture of Carbureted Water-Gas, of which the following is a specification.

10 The principal object of the present invention is to effect a saving of fuel and other objects of the invention are to obtain increased candle power in the gas from a given amount of oil; to localize the 15 heating effect of the secondary combustion of fuel or producer gas in preparation for the subsequent carburization of the water gas; to discharge the blast gases from the apparatus at relatively low temperature 20 while maintaining sufficient heat in the apparatus for properly heating the oil; to effect the most advantageous distribution of heat in the apparatus; and to vary the rapidity of flow of the oil gas through the 25 fixing chambers, if desired.

Another object of the invention is to deliver the blast gas for secondary combustion with air to a comparatively hot surface rather than to a surface made 30 comparatively cool by the previous vaporization of oil upon it or in its vicinity.

The invention will be claimed at the end hereof, but will be first described in connection with the embodiment chosen 35 from other embodiments for the sake of illustration in the accompanying drawings, in which—

Figure 1, is a top or plan view of apparatus embodying features of the invention, 40 and Fig. 2, is a sectional view, partly in elevation, taken on the line 2—2 of Fig. 1.

In the drawings 1, is a generator having steam and air connections 2 and 3, and otherwise adapted for the production of 45 blast and blue water gas alternately.

4, is an off-take from the generator that may be made to communicate with the chamber 5 or the chamber 6, according to the position of the valves 7 and 8 in the branches 50 9 and 10. The chambers 5 and 6 are duplicates of each other and intercommunicate by means of the connection 11 arranged at the base thereof. Each of these chambers 5 and 6, contains checkerbrick or the like 12, with space above and below it and each of 55 these chambers is provided with valved means 13 for introducing oil and with means 14 for introducing air and with an off-take 15. It may be said that when one of the chambers 5 or 6 is operating, during 60 a blow and run, as a carbureter the other chamber is operating as a fixing chamber and that during the next blow and run the chamber which was operating as a fixing chamber becomes a carbureter and the 65 chamber which was operating as a carbureter becomes a fixing chamber, with the result that the combustion of blast gas takes place in the vicinity of checkerbrick left comparatively hot, for example, about 70 1300° F., instead of in the vicinity of checkerbrick left comparatively cool by the vaporization in its vicinity of oil. The off-takes are provided with stack valves 16 and with branches 17 that lead to wash 75 boxes 18. The wash boxes are connected with a gas off-take 19 having valved branches 20 and 21 that lead to the respective wash boxes.

It is unnecessary to describe that blast 80 gas and blue water gas are alternately made during the blow and run in the generator 1, because that is well understood and in the following description it will be assumed that the generator is operating in that way. 85 Blast gas is delivered from the generator to the chamber 5, the valve 7 being open and the valve 8 being closed. The blast gas is burned in the chamber 5 by the addition of air, heating the top of the checkerbrick 90 comparatively hot, for example, to 2300° F., the hot products pass down through the chamber 5, through the connection 11 up through the chamber 6 and escape by the stack valve 16 of that chamber, which 95 is open. At first these blast gases escape at relatively low temperature, for example, at about 1000° F., but as the blow continues their temperature rises to about 1300° F., which is the usual temperature. The average, however, is lower than usual. These gases raise the temperature of the checkerbrick in the chamber 6 so that it is approximately 1300° F. The stack valve 16 of the chamber 5 is closed. Blue water gas 100 then follows the same course, with the exception that both stack valves are closed and the valve in the branch 21 is open and

the valve in the branch 20 closed. Oil or the like is introduced at 13 and in evaporating reduces the temperature of the checkerbrick in the chamber 5 to, for example, 5 1000° F., but the carbureted water gas in traversing the previously heated checkerbrick in the two chambers leaves the checkerbrick in the top of the chamber 6 at about 1300° F. At the next blow, the blast 10 gas is introduced at the top of the chamber 6, the valve 7 being closed, the valve 8 open, the stack valve 16 of the chamber 6 closed and the stack valve of the chamber 5 open. The blast gas in the chamber 15 6 meets checkerbrick at relatively high temperature, about 1300° F., as has been said and for this reason on the application of the secondary air through connection 14 of the chamber 6, the blast gas even though 20 lean, that is low in CO, which is the case particularly at the beginning of the blow, immediately burns thus localizing the combustion and not stringing it along down through the checkerbrick of the chamber 6. 25 The temperature of the checkerbrick, as has been said, is about 1300° F., so that the work of combustion of the blast gas is to raise it about 1000° F. to 2300° F. The products of combustion pass through the 30 chamber 6, the connection 11 and chamber 5, meeting progressively cooler checkerbrick, and escape from its stack 16, at as has been said about 1000° F. (the temperature to which the top of the checkerbrick in 35 the chamber 5 was reduced by vaporization of oil) and then at increasing temperature to 1300° F., the average, however, being less than 1300° F. as is usual. At the next run the blue water gas is carbureted in the 40 chamber 6 cooling the top of its checkerbrick to about 1000° F. and the carbureted water gas passes by way of the connection 11, through the chamber 5, the branch 20 to the off-take 19, the valve in the branch 45 21 being closed and this carbureted water gas leaves the chamber 5 at a temperature of about 1300° F. At the next blow the blast gas is burned in the chamber 5 in the vicinity of checkerbrick at 1300° F. 50 It will be noted that the vaporization of oil cools the checkerbrick in its vicinity in one chamber to about 1000° F., which is usual, but at the next blow the blast gas is not introduced into that chamber for combustion with air, but is introduced into the other chamber and burned in the vicinity of checkerbrick the temperature of which is comparatively high, for example 1300° F., so that the combustion of the blast gas, 55 even though lean, is localized and is not strung out through the apparatus which is 60

thus properly prepared for the vaporization of oil. Products of combustion on their way to the stack traverse progressively cooler checkerbrick to which they impart their heat, escaping from the stack at first at relatively low temperature and afterward at high temperature, the average temperature, however, being comparatively low. The air connections 14 are shown as applied to the pipes 9 and 10, but if preferred one air connection 14^a applied to the outlet 4 can be used. By manipulating the valves 7 and 8 so that they are both opened during the run it is possible to pass only a part of the blue water gas through the chamber in which carburization is taking place and the rest of the blue water gas into the other chamber where it is met by the carbureted water gas and led off from the apparatus. 70 In this way the rapidity of flow of the oil gas through the chambers can be varied. 75 While, in the foregoing description, reference is made to temperatures it is not the intention to limit the invention to specific 80 temperature but the latter are mentioned only for the sake of description so that those skilled in the art will readily understand the improved results accomplished. Without reference to temperatures it may 85 be said that the blast gas is burned at a part of the apparatus which is comparatively hot and from which the gas has been previously led off as distinguished from being burned at a part of the apparatus which 90 is comparatively cool by reason of the previous vaporization of oil, and further that the products of combustion of the blast gas 95 are led to the stack through progressively cooler apparatus instead of through progressively hotter apparatus. 100

What I claim is:

The method of making carbureted water gas which consists in alternately making blows of blast gas and runs of blue water 105 gas, passing the blows and runs in succession and in reverse direction through a chamber carbureting the successive runs alternately at separated points in the chamber whereby they are cooled, burning successive blows alternately at points of relatively high temperature opposite to those at which the preceding carbureting was done, and leading off the carbureted gas and products of combustion alternately at 110 opposite ends of the chamber.

In testimony whereof I have hereunto signed my name.

OWEN BROOKE EVANS.
